UNITED STATES PATENT OFFICE.

WILLIAM DIETER, OF NEW YORK, N. Y.

RUNNING-GEAR FOR VEHICLES.

SPECIFICATION forming part of Letters Patent No. 766,226, dated August 2, 1904.

Application filed September 17, 1903. Serial No. 173,498. (No model.)

To all whom it may concern:

Be it known that I, WILLIAM DIETER, a citizen of the United States, and a resident of the borough of Brooklyn, city of New York, county of Kings, and State of New York, have invented certain new and useful Improvements in Running-Gear for Vehicles, of which the following is a specification, reference being had therein to the accompanying drawings, which form a part thereof.

My invention relates to the running-gear of vehicles, and more particularly to that class thereof wherein the side-bars or reaches comprise leaf or analogous springs.

15 The object of the invention is to provide a running-gear of this type wherein the factor of safety will be high without materially affecting the spring action.

20 A further object is to provide means whereby the side springs or spring-reaches may be connected to the axles in a manner to permit the unrestricted side oscillation of the vehicle-body and the tilting of the axles without affecting the spring tensions and to permit the 25 longitudinal adjustment of the said side springs or spring-reaches to conform to other structural details of the vehicle or to properly tension the springs.

20 A still further object is to provide such a means of connection which will be self-lubricating and substantially dust-proof and so constructed and arranged as to present an extensive holding area and to contain no parts which through jars and jolts can be loosened, 35 or lost, with possibilities of resulting accident; and a still further object is to provide in a vehicle a side spring or spring-reach which will be of simple construction capable of being quickly and conveniently assembled.

40 The invention broadly consists in a side reach comprising a plurality of independent springs arranged one above the other, means whereby a vehicle-body may be mounted thereon, and means whereby the opposite ends 45 of said springs may be connected to the front and rear axles comprising a shackle-plate, a pivotal connection between each plate and its axle, having its axis at right angles to the axle, yokes on said plates concentric with 50 said pivotal connection, and means whereby

the adjacent ends of said springs are respectively connected to one of said yokes on each axle, and also in certain details as to construction and arrangement of parts, as hereinafter set forth and described, and more particularly 55 pointed out in the claims hereto appended.

Referring to the drawings, Figure 1 is a side elevation of a side spring or spring-reach embodying my invention, the vehicle-body and wheels being indicated in dotted lines. Fig. 60 2 is an enlarged view of the means connecting said springs to the axle, said view being broken away and the interior construction thereof shown partly in elevation and partly in section. Fig. 3 is an end view thereof as 65 indicated by the arrow and numeral 3, Fig. 2; and Fig. 4 is a side elevation of the axle-collar and its sleeve.

Like letters refer to like parts throughout the several views.

70 In the drawings, *a a'* indicate, respectively, independent springs arranged one above the other, which extend longitudinally of the vehicle and are connected to the front and the rear axle. The vehicle-body is mounted on 75 the central part of the reach so formed, and a pedestal or bolster *b* is disposed between said springs to give a certain entity of structure thereto and insure the maintenance of the proper relation of the springs and also the 80 transmission of pressures from one to the other. Said body is secured in position by bolts passing through both springs and said bolster or pedestal *b*, a suitable face-plate being interposed between said bolts and the lower 85 spring. These springs may be of equal strength and similarly tensioned, if desired; but under some conditions I prefer to have them differ both in strength and tension, that the vibrations of one when running may so 90 affect the other as to break any rhythmic vibrations, and thus limit the extent and duration of the oscillations of the vehicle-body. The ends of said springs may be connected to the axles through any desired agency; but 95 preferably I employ a direct coupling which has the function in addition to merely forming a joinder of these parts of permitting a lateral swing of the springs and tilting of the axles, or either of them, while containing an 100

extensive holding area which automatically takes up or lets out the springs at one end and simultaneously lets it out or takes it up at the other to an equal extent with the oscillations 5 of the body. This attachment or connection has the further advantage that in assembling it may be adjusted to compensate for any spring-tension irregularities and to regulate the tension of the side springs or spring-10 reaches, and when once set the interlocking of the screw-threads alone holds it in place. It cannot therefore through a working loose or wearing of parts vary this relation or permit the uncoupling of the springs from the 15 axle. This coupling comprises an interiorly-screw-threaded sleeve *d*, mounted on the axle *c* by means of a collar *c'*, which latter may be attached to the axle in any desired manner, as by being shrunk, keyed, or brazed thereon. 20 These parts are preferably made integral, as of a single casting, and the thread tapped therein may be of any desired form. Coöperating with the sleeve *d* is a screw-threaded tongue *e*, the threads of which mesh with those 25 of the said sleeve. The tongue *e* is provided with a collar *e'* and a tang *e''*, which carries the yoke-plate *f*, to which the springs *a a'* are secured. For convenience in handling in the shop these parts—the yoke-plate and the tongue *e* 30 and its appurtenances—are made separately and united after being finished, the tang *e''* being adapted to enter an opening in the said yoke-plate to a point where the collar *e'* abuts against said plate and its end upset to firmly 35 secure the parts together. This construction, however, is merely one of convenience to reduce the labor and expense of handling and to facilitate the assembling of parts and is not essential to the invention. 40 The tongue *e* is provided with a central lubricant-chamber *g*, which feeds oil to the sleeve through the openings *g'* in said tongue. Preferably this chamber is filled with waste 45 saturated with the lubricant to avoid an excessive feed thereof to said sleeve. To exclude dust from said threads and the lubricant-chamber, I provide the caps *h h'*, which respectively close the ends of the sleeve *d*. These caps may be either screw-threaded or 50 merely friction-caps. One, as *h*, is an ordinary cup-shaped cap, while the other, *h'*, is open at one end in order to pass over and closely envelop the collar *e'*, and thus facilitate its application to the sleeve *d* and permit 55 slight longitudinal movement of the tongue *e* and its appurtenances.

The yoke-plate *f* is provided with oppositely-disposed yokes *f' f''*, each provided with transverse bolt-holes and having there-60 between the curved spring-seats *f''' f''*. The said yokes are disposed on opposite sides of the axis of the tongue *e* and substantially equidistant therefrom or concentric therewith. The springs *a a'* are connected to said 65 plates by placing the end of each said spring

between the arms of one of said yokes and passing a bolt *k* through the said arms and the turned end of the spring, said bolts being fixed in this position. The spring-seats *f''' f''* not only serve to relieve said bolts of certain 70 shearing strains, but also contribute to the strength of said plates.

The tongue *e* at each end of the side springs or spring-reaches is similarly screw-threaded with the one at the other end, so that a lateral 75 oscillation of said springs will cause one plate to travel toward and the other from its sleeve *d* to an equal extent, thus relieving the springs *a a'* from any longitudinal compression or expansion from this source. The tilting of 80 either axle alone will not materially affect the springs, as the tongue *e* can turn freely in its sleeve and the arc inscribed by the axle end is not sufficient to do otherwise than tension the springs slightly. 85

The operation of the above-described coupling is apparent. The screw-threaded tongue *e*, meshing with the screw-threads of the sleeve *d*, permits the regulation of the distance between the spring-yokes *f' f''* independently of the axles to a limited extent, and thus permits an independent adjustment 90 of the spring tension on each side of the vehicle in assembling to produce a properly-balanced vehicle. The manner of attaching the 95 springs facilitates this adjustment. This construction and arrangement avoids the necessity of finely finished and adjusted parts without sacrificing any advantages. The coöperating screw-threads give an extended holding 100 area and provide a means of attachment which admits of oscillation and at the same time one which will not permit the separation of the springs from the axle except by the stripping of heavy threads, an all but impossible contingency. The threads are automatically lubricated to prevent undue wear or binding of parts through rust, and the said threads are practically dust and dirt proof. 105

In action the side oscillations of the vehicle-body do not distort the springs, the connection with the axles turning instead of subjecting the springs to a torsional strain at their weakest point. This turning movement, however, does not subject any part to 110 undue strains, as one tongue *e* takes up the spring to an extent equal to that which the other lets out, thus maintaining the equilibrium of spring tensions on both parts. 115

The operation of the springs *a a'* is substantially as follows: Whether the springs be of the same or different tensions, under normal loads and conditions the upper spring will carry the main load, and the lower spring will not be pushed to its full capacity. With 120 the increase of load or the further compression of the upper spring, however, the other will assume more of the load, and thus relieve the other to a certain extent and at the same time break up the rhythm of oscillation. 125 130

tion of the vehicle - body. The bolster or pedestal *b* aids in bringing the second or lower spring into action at the desired period and also in case of the breakage of the upper 5 spring will cause said lower spring to at once assume the full load. By making the springs of different strengths and tensions I merely emphasize the above mode of operation, more positively assuming the load and breaking up 10 the oscillations of the other spring and the vehicle-body.

The structure heretofore described is duplicated on each side of the vehicle; but in the specification and claims but one side spring 15 or spring-reach is shown and described.

It is not my intention to limit the invention to the precise construction herein shown and described, as such may be varied without departing from the spirit and scope of my 20 invention.

Having described the invention, what I claim as new, and desire to have protected by Letters Patent, is—

1. In a running-gear for vehicles, a spring- 25 reach comprising a plurality of independent springs arranged one above the other, means whereby a vehicle - body may be attached thereto, and means connecting the opposite ends of said springs to the front and the rear 30 axles comprising a shackle-plate, a pivotal connection between each plate and its axle, having its axis at right angles to the axle, yokes on said plate concentric with said pivotal connection, and means whereby the adjacent ends of said 35 superposed springs are respectively connected each to one of said yokes.

2. In a running-gear for vehicles, a spring- 40 reach comprising a plurality of independent springs of different strength or tension arranged one above the other, means whereby a vehicle - body may be attached thereto and means connecting the opposite ends of said springs to the front and the rear axles comprising a shackle-plate, a pivotal connection 45 between each plate and its axle, having its axis at right angles to the axle, yokes on said plate concentric with said pivotal connection, and means whereby the adjacent ends of said 50 superposed springs are respectively connected each to one of said yokes.

3. In a running-gear for vehicles, a spring- 55 reach comprising a plurality of independent springs arranged one above the other, a bolster or pedestal between said springs approximately centrally thereof, means whereby a vehicle - body may be attached thereto and means connecting the opposite ends of said springs to the front and the rear axles 60 comprising a shackle-plate, a pivotal connection between each plate and its axle, having its axis at right angles to the axle, yokes on said plate concentric with said pivotal connection, and means whereby the adjacent ends of

said superposed springs are respectively connected each to one of said yokes. 65

4. In a running-gear for vehicles, the combination with a spring-reach and means whereby a vehicle-body may be attached thereto, of an interiorly-screw-threaded sleeve mounted 70 on each axle, screw-threaded tongues meshing therewith respectively and means carried by said tongues whereby the opposite ends of said spring-reaches are connected thereto.

5. In a running-gear for vehicles, the combination with a spring-reach and means whereby a vehicle-body may be attached thereto, of a sleeve mounted on each axle, a tongue rotatably mounted therein, said tongues each being provided with a lubricant-chamber dis- 75 charging into said sleeve and means carried by said tongue whereby the opposite ends of said spring-reaches are connected thereto.

6. In a running-gear for vehicles, the combination with a spring-reach and means whereby a vehicle-body may be attached thereto, of an interiorly-screw-threaded sleeve mounted 80 on each axle, screw-threaded tongues meshing therewith respectively, said tongues each being provided with a lubricant-chamber dis- 85 charging into said sleeve, and means carried by said tongues whereby the opposite ends of said spring-reaches are connected thereto. 90

7. In a running-gear for vehicles, the combination with a spring-reach and means whereby a vehicle-body may be attached thereto, of an interiorly-screw-threaded sleeve mounted on each axle, screw-threaded tongues meshing therewith respectively, said tongues each being provided with a lubricant-chamber dis- 95 charging into said sleeve, dust-proof caps inclosing the opposite ends of said sleeve, and means carried by said tongues whereby the opposite ends of said spring-reaches are connected thereto. 100

8. In a running-gear for vehicles, the combination with a spring-reach comprising a plurality of independent springs arranged one above the other and means whereby a vehicle- 105 body may be attached thereto, of an interiorly- screw-threaded sleeve mounted on each axle, screw-threaded tongues respectively meshing therewith, and a yoke-plate carried by each said tongue comprising yokes disposed on the opposite sides of the axis of said tongues and means whereby said springs may be secured to said yokes respectively. 115

9. In a running-gear for vehicles, the combination with a spring-reach comprising a plurality of independent springs arranged one 120 above the other and means whereby a vehicle- body may be attached thereto, of an interiorly- screw-threaded sleeve mounted on each axle, screw-threaded tongues respectively meshing therewith, a collar thereon, a yoke-plate carried by each said spring comprising yokes disposed on the opposite sides of the axis of said tongues, said tongues being provided with a lu- 125

bricant-chamber discharging into said sleeve, a cap inclosing one end of said sleeve, a second cap enveloping the other end thereof and surrounding said tongue and bearing against said collar, and means whereby the said springs may be secured to said yokes respectively.

5 In witness whereof I have hereunto affixed

my signature, this 1st day of September, 1903,
in the presence of two witnesses.

WILLIAM DIETER.
